DRAWER PULL

William Doyle Watt, Jr., Grand Rapids, Mich., assignor
to Keeler Brass Company, Grand Rapids, Mich.

Filed June 25, 1971, Ser. No. 157,070

Term of patent 14 years

Int. Cl. D8—06

U.S. Cl. D8—171

FIG. 4

FIG. 2

FIG. 3

FIG. 1 is a front elevational view of a drawer pull;
FIG. 2 is a side elevational view thereof;
FIG. 3 is a side cross-sectional view thereof taken along
the line III—III of FIG. 1; and
FIG. 4 is a top plan view thereof.

I claim:

The ornamental design for a drawer pull, substantially
as shown.
